ENCLOSURE FOR A TRANSMITTING ANTENNA

John F. Redman, Jr., 4311 W. 70th St.,
Prairie Village, Kans.

Filed Dec. 8, 1958, Ser. No. 53,676

Term of patent 14 years

(Cl. D26—14)

Fig. 2.

Fig. 1.

Fig. 1 is a side elevational view of an enclosure for a transmitting antenna, showing my new design, the appearance from all sides being substantially the same; and

Fig. 2 is a bottom plan view thereof.

The fragmentary broken line showing of a mast in Fig. 1 is for illustrative purposes only.

I claim:

The ornamental design for an enclosure for a transmitting antenna, as shown and described.
